CARRIAGE CONTROL FOR TYPEWRITERS
AND THE LIKE

Fred Becker, Queens Village, N. Y., assignor to,
Underwood Corporation, New York, N. Y., a corporation of Delaware

Application December 30, 1946, Serial No. 719,158

5. Claims. (CL 197—82)

1.

This invention relates to typewriting machines and the like, and more particularly to pawl-and-ratchet devices associated with the carriage letter-feed mechanism and operative incident to return of the carriage.

An object of the invention is to provide, in a carriage-control mechanism, an improved ratcheting device by which overbanking of the carriage upon returning it to start a new line of typing is obviated.

In typewriters of certain construction wherein the margin-regulating mechanism is at the front of the frame-like carriage and the letter-feed mechanism with its carriage-carried rack is adjacent the rear of the carriage, there is chance of overbanking occurring, particularly when the carriage is returned manually with undue force or in power carriage-return machines. This overbanking is due in part to the inherent yieldable character of the carriage frame and to a backlash of the mechanisms involved in banking the carriage at the left hand or line-start margin. In conventional mechanisms the actual overbanking results from the pawl-and-ratchet device associated with the letter-feed mechanism ratcheting a letter-feed step beyond that determined by the margin regulator, so that after banking the carriage at the left margin, when the letter-feed escapement resumes control of the carriage, a discrepancy of one letter space in the line-start position of the carriage is had.

The present invention obviates this fault by providing a ratchet mechanism in which the pawl may follow along with the ratchet wheel or pinion an angular distance substantially greater than the pitch of the ratchet teeth, without ratcheting into a succeeding tooth. This enables the ratchet wheel or pinion to rotate, for instance, an angular distance equivalent to, say, one and a third letter spaces, during the instant in which banking occurs, without the associated pawl ratcheting into a succeeding tooth. Thus the ratcheting device will maintain the same interrelation between the carriage and letter-feed mechanism and will accommodate an appreciable over-travel of the carriage rack induced by the springing of the carriage frame and the taking up of backlash in the carriage-arresting parts.

Other objects of the invention are in part obvious and in part particularly pointed out as the following description of a preferred embodiment of the invention proceeds.

In the drawings:

Figure 1 is a front elevational view of a letter-feed escapement mechanism embodying the im-

2.

proved pawl and ratchet device, the mechanism and device being in the quiescent condition with the carriage at rest in position to start a new line of typing.

5. Figure 2 is a view similar to Figure 1 but showing the parts of the feed mechanism and ratchet device in the positions which they may take at the instant the carriage is banked at the line-start or left hand margin, that is, just after the return of the carriage is terminated; and

Figure 3 is a diagrammatic plan view of a typical typewriter carriage showing in dot-and-dash outline, somewhat exaggerated, the yield of the carriage incident to this banking.

15. The invention is advantageous particularly in its operative relation with the letter-feed mechanism of the typewriter. This mechanism may be of any well-known kind and operates to advance the paper-supporting carriage one letter-space step incident to the typing of each character of the typing line. When the typed line is completed the carriage is returned, Figure 3, either manually or by power, to the line-start position as determined by the engagement of a 20 counterstop 5 on the carriage 6 with an adjustably positionable margin stop 7 on the typewriter main frame.

25. Apart from the improved ratchet device of the invention, the letter-feed escapement mechanism illustrated is of conventional construction, a brief description of which follows.

30. A toothed rack 8 is mounted on the carriage and meshes with an escapement pinion 9 which also serves as a ratchet wheel, these members 8 and 9 comprising an operative connection between the carriage 6 and an escapement mechanism 10. This mechanism includes mainly an escapement wheel 11 with which a pivoted stepping dog 12 and a detent dog 13 cooperate in the usual manner to control the letter-feed steps of the carriage. The carriage 6 is actuated in the direction of the arrow in Figure 1 by the usual carriage spring drum, not shown. The feed dogs 12, 13 are mounted on a dog rocker 14 rockable on pivots 15. The dog rocker is actuated by the type actions of the typewriter through a universal bar, not shown, to rock the dog rocker rearwardly. A spring 16 connected to the stepping dog 12 tends to pull this dog rightward toward a stop 17 and is biased so as to also restore the dog rocker 14 to its forward, inactive position. The pinion or ratchet 9 and the escapement wheel 11 are mounted to rotate independently on a stud 18 secured to a frame 20 which also mounts the pivots 15. The tension of the carriage spring

drum, tending to move the carriage rack 8 leftwardly and to rotate the pinion 9 counterclockwise, is transmitted from pinion 9 to the escapement wheel 11 by a novel ratchet pawl 22, hereinafter described. The teeth of the escapement wheel 11 are beveled as shown and the detent dog 13 has its leading edge beveled on the far side. As the dog rocker 14 rocks rearwardly the detent dog 13 engages the same tooth of wheel 11 that was engaged by the stepping dog 12, the bevels on dog 13 and the escapement wheel teeth facilitating this engagement. As dog 12 leaves the wheel tooth, spring 16 swings this dog leftward against stop 17 so that dog 12 is in a position to engage the next tooth of wheel 11. This occurs incident to the type action restoring, the dog rocker 14, therefore, returning to its forward position. As detent dog 13 leaves the wheel tooth and dog 12 assumes engagement with the next tooth, the tendency of the carriage to move leftward causes the escapement wheel 11 to rotate until dog 12, coming into engagement with a stop not shown, arrests wheel 11 in the position shown in Figure 1. Each letter-feed step of the carriage, including word spaces, is effected by a similar operation of the escapement mechanism.

Upon completion of a line of typing the carriage is returned to the line-start position as determined by the left-hand margin stops 5, 7. Before the carriage begins to return, the escapement mechanism and ratchet device are in the condition shown in Figure 1. As the carriage is moved in the return direction indicated by the arrow in Figure 2, the corresponding movement of the rack 8 rotates pinion 9 clockwise and this rotation, transmitted to the escapement wheel 11 via the tensioned ratchet pawl 22, rotates the escapement wheel 11 slightly in a counter-feed direction until a back-check dog 23 mounted on the rocker 14 is engaged by the immediately preceding tooth of wheel 11. This check dog 23 is urged leftwardly by a spring 24 to rest against a stop 25, the spring yielding to permit the check dog 23 to swing rightwardly and thus ratchet idly over each tooth of the escapement wheel during the letter-feed action. As the carriage continues its return travel the pawl 22 ratchets over each tooth of the pinion 9 until the return of the carriage is terminated at the line-start margin.

Pawl 22 is mounted on the escapement wheel 11 in such manner as to be capable preferably of both pivotal and endwise or linear movement. A stud 27 secured to wheel 11 projects from the face thereof into a slot 28 in the pawl, the slot extending substantially lengthwise of the pawl. A spring 30 wound about a pin 31 on wheel 11, has one end anchored in the wheel and has the other end pressing against the end of the pawl 22 opposite its slotted end, a groove in the pawl receiving the curved end of the spring. A cam pin 32 secured to wheel 11 coacts with a cam 33 formed on pawl 22. The shape of the cam face 33 is such as to guide the pawl in a generally endwise or linear movement as generated by the action of the pawl tooth 22' as the pinion 9 turns clockwise and the pawl tooth follows along to a predetermined extent without ratcheting. The two positions taken by the pawl 22 at the start and at the conclusion of this follow-up action are shown in Figures 1 and 2, respectively. This motion of pawl 22, against the tension of spring 30, is taken while a straight or nearly straight intermediate portion of cam 33 rides along pin 32, and is terminated by an angular face or shoulder 34 of the cam coming against the pin. At the

other end, the cam face may take a slight turn from the straight portion, as indicated at 35, which acts to cam the pawl tooth 22' into the tooth space of pinion 9. Spring 30 is arranged so as to exert a pressure generally endwise of the pawl, tending to move the pawl, by coaction of cam 33, to the position of Figure 1. The contour of the effective portion of cam 33 may be varied somewhat from that shown, it being noted that the function of this cam is to cause the pawl tooth 22' to seat positively into the tooth space of pinion 9 when no ratcheting takes place as during letter-feeding, and to cause the pawl tooth to move along with the same pinion tooth to a certain extent of, say, one and one-third times a tooth pitch or letter space without ratcheting.

The extent of follow-up movement of pawl 22 may be modified to suit various conditions in the typewriter. It is, however, desirable to limit this movement to a maximum of, say, one and a fraction letter-spaces as the back-spacing mechanism of the typewriter should operate to back-space the carriage to a corresponding extent. It may be here noted that the tooth pitch of pinion 9 is such that there is one tooth for each letter space or, in other words, if the letter spacing is ten per inch, there are ten tooth-spaces in pinion 9 for each inch of carriage travel.

The operating effect of the pawl-and-ratchet device in obviating overbanking will now be described. It will be noted that at the start of carriage return the escapement mechanism assumes the condition shown in Figure 2 but pawl 22 has not as yet moved relatively to wheel 11 and its tooth 22' is still engaged between the two teeth of pinion 9. It will be further noted that the escapement wheel 11 has rotated clockwise a slight degree from the Figure 1 position, as indicated by the rightward displacement of the dotted arrow on rack 8 from arrow 36 in Figure 2, and that pawl 22 has moved bodily with wheel 11. As the carriage continues to be returned pinion 9 now turns while wheel 11 remains stationary, being held by check-dog 23. After pinion 9 has turned a little more than, say, one and a third tooth spaces, during which rotation pawl 22 has moved along with the pinion, the endwise movement of pawl 22 is stopped by shoulder 34 and the pawl ratchets into the next tooth space. This ratcheting action occurs once for each letter-space distance of carriage return and until the carriage is stopped by the margin stops 5, 7. If the carriage were to be brought up lightly to the line-start position so that the margin stops 5, 7 just contacted lightly, the escapement mechanism 11 would be as shown in Figure 2 but the pawl 22 would nevertheless be in its inactive position as in Figure 1. To clarify the description, the position of slight advance of the escapement wheel 11 which it assumes during carriage return, may be disregarded except to note that the point of engagement of the margin stops 5, 7 is such as to allow for this slight advance, and that after carriage return the carriage settles back a corresponding extent as the escapement mechanism, particularly the feed dog 12, resumes control of the carriage position.

For purposes of description, it is assumed, as aforementioned, that the stops 5, 7 have just contacted lightly and that the impact of stopping the forceful return of the carriage has not as yet had its effect to tend to overbank the carriage. Under this condition, as before described, the escapement wheel and the feed and check dogs

12, 13, 23 are in the Figure 2 position but the pawl tooth 22' is still in the position of engagement with pinion 9 as shown in Figure 1. This relation of pinion 9 and wheel 11 is indicated graphically by the two arrows 37 in Figure 1 being aligned with each other. As the forceful banking of the carriage occurs, with the tendency of overbanking as indicated by the dot-and-dash outline of the carriage in Figure 3, the rack 8 moves rightwardly to an extent such as that indicated by the rightmost or solid arrow on rack 8 in Figure 2. This extent of course varies somewhat in accordance with the force of impact at the instant of banking the carriage, but for the purposes of this description it may be assumed to be about one and one-third letter spaces. The corresponding displacement of pinion 9 relatively to wheel 11 is shown by the displacement of the two arrows 36 in Figure 2. The tooth of pinion 9 with which pawl tooth 22' had been engaged before the tendency to overbank occurred is marked with a cross in Figures 1 and 2. During this rotation of pinion 9, the pawl tooth 22' has moved out from the tooth space of pinion 9 and pawl 22 has advanced bodily with the pinion, so that notwithstanding the advance of pinion 9 to an extent greater than a tooth space, the pawl has not ratcheted into the next tooth space. Instead, at the end of the overbanking action, the pawl tooth 22' is still in such position that it will reengage in the same tooth space of pinion 9 that it engaged when the margin stops 5, 7 contacted lightly. In other words, the same letter space relation between the carriage 6 and the escapement mechanism 10 is maintained notwithstanding that the carriage rack 8 has overtraveled an appreciable degree beyond that at which the stops 5, 7 determine the line-start position. From this it will be seen that after the carriage has been fully banked and the rack 8 settles back to its normal relation with the margin stops, the pinion 9 will recede to a position in which the arrows 37 are again aligned and the pawl tooth 22' will again seat into the pinion tooth space with which it was previously engaged. During this recessive action, pawl 22, under the camming action assisted by spring 30, retards from the Figure 2 position to the Figure 1 position as the arrows 37 move toward registry with each other. Meanwhile rack 8 has been restored to its position indicated by the dotted arrow. Following this the carriage settles to its normal letter-feed position as escapement wheel 11 resumes its Figure 1 position to again come under control of the feed dog 12 as the escapement mechanism resumes control of the carriage position.

Although in this application, there is specifically described one embodiment which the invention may assume in practice, it will be understood that the invention may be modified and embodied in various other forms without departing from its spirit or the scope of the appended claims.

What is claimed as new is:

1. In a typewriter or like machine, the combination with a carriage letter-feed escapement mechanism having dogs cooperating with a toothed escapement member to control the letter-feed steps, of a one-way drive device interposed between the carriage and the escapement mechanism and effective to enable return of the carriage without a ratcheting action of the escape-

- ment mechanism, said device including a toothed ratchet and a pawl and mounting means therefor having provision for limited movement of the pawl in a direction generally along the line of the ratchet tooth travel occurring incident to returning the carriage.
2. In a typewriter or like machine, the combination with a carriage letter-feed mechanism having dogs cooperative with a toothed escapement member to control the letter-feed steps, of a pawl-and-ratchet device interposed between the carriage and the letter-feed mechanism and effective to enable return of the carriage without a ratcheting action of the letter-feed mechanism, said device including a pawl and mounting means therefor providing for pivotal movement and lineal movement of the pawl, the latter to an extent greater than the pitch of the ratchet teeth.
- 10 3. In a carriage control for typewriters and the like having a letter-feed escapement, a line-start margin device and an operative connection between the carriage and the escapement including a ratcheting device operative incident to returning the carriage to the line-start position, said ratcheting device comprising a pawl and mounting means therefor having provision for pivotal movement and linear endwise movement of the pawl to an extent greater than a step of letter feed.
- 20 4. In a carriage control for typewriters and the like having a letter-feed mechanism and a line-start margin device, the letter-feed mechanism including an escapement wheel and a back-check 35 dog, an operative connection between the carriage and escapement wheel including a toothed ratchet coaxial with the escapement wheel, a spring-pressed pawl cooperating with said ratchet, and means mounting said pawl on the escapement 40 wheel for limited movement relatively to said wheel and in the general direction of rotation of the ratchet teeth taken incident to returning the carriage to the line-start position determined by the margin device.
- 45 5. In a carriage control for typewriters and the like having a letter-feed mechanism and a line-start margin device, the letter-feed mechanism including an escapement wheel and a back-check dog, an operative connection between the carriage 50 and escapement wheel including a toothed ratchet coaxial with said escapement wheel, a spring-pressed pawl cooperating with said ratchet, a pin-and-slot connection mounting said pawl on the escapement wheel, and a cam-and-follower 55 device between said pawl and wheel, said connection and said cam device coacting to cause said pawl to follow along with the ratchet teeth to a limited extent during rotation of the ratchet incident to returning the carriage to the line-start position.
